UNITED STATES PATENT OFFICE.

SAM MITZENMACHER, SR., AND SAM MITZENMACHER, JR., OF CHICAGO, ILLINOIS.

WINDOW-CLEANING DEVICE.

Application filed August 31, 1922. Serial No. 585,576.

To all whom it may concern:

Be it known that we, SAM MITZENMACHER, Sr., and SAM MITZENMACHER, Jr., citizens of the United States, and residents 5 of the city of Chicago, county of Cook, and State of Illinois, have invented certain new and useful Improvements in Window-Cleaning Devices, of which the following is a specification.

10 Our invention relates to a window cleaning device and has for its object to provide means for washing the outside of a window as well as the inside thereof while standing on the inside of a room and window.

15 Other objects will appear hereinafter.

The invention consists in the combinations and arrangements of parts hereinafter described and claimed.

20 The invention will be best understood by reference to the accompanying drawings forming a part of this specification, and in which—

Fig. 1 is an elevational view of the preferred form of our invention;

25 Fig. 2 is an enlarged vertical sectional view thereof taken on line 2—2 of Fig. 1; Fig. 3 shows a modified form of our invention, viewed on line 3—3 of Fig. 4;

Fig. 4 is an enlarged vertical sectional 30 view taken on line 4—4 of Fig. 3, and

Fig. 5 is a view of another modified form of our invention.

The form of our invention illustrated in Figs. 1 and 2 comprises a cylindrical housing 10 provided with a bracket 11 which is arranged to embrace the upper sash rail 12 of a window 13, for mounting the housing on either the outside or the inside of a window, whichever side is to be cleaned. A 35 coiled spring 14 has one end fastened in the upper part of said housing, and a cleaning member or means 15 is attached to the other end of said spring, as by means of diverging arms 16 releasably connected with one 40 end to said spring and with the other end to said cleaning means. A bracket 17 is mounted on the outer part of said housing and beneath the same for guiding said spring and preventing it and the attached 45 cleaning means 15 from moving or swinging outward or from the window.

The cleaning member 15 preferably comprises a brush or body member with means in the form of bristles 18 on one side for 50 washing the window, and with means in the form of a rubber strip 19 fastened to said

member 15, on the side opposite the bristles, for removing the moisture from the window and for drying it. A receptacle or liquid container 20 is placed at the bottom of the window for receiving and moistening the bristles or washing means 18. Any suitable washing means and drying means may be substituted for the bristles and the rubber strip, respectively, and the liquid container 60 or dispenser may consist of any suitable device and may be arranged in any suitable manner.

A flexible member or cable 21 is provided for manually operating the device, and is 70 preferably fastened to the cleaning member, as by means of a hook 22 which engages detachably in the eye of a screw 23 fastened to said member 15.

The device is conveniently passed from 75 the room through the window, above the lowered upper sash, and the bracket 11 is readily clamped onto the upper rail of the window sash, while the frame 10 extends outward along the window frame, if the outside of the window is to be cleaned, and the cleaning means engages the outer side of 80 the window pane. The descending cable 21 may be manually engaged and drawn downward through the slightly raised lower window, thereby placing the spring under tension, which spring thereafter moves said cleaning means upward upon ceasing of the manual pull on said cable.

85 Figs. 3 and 4 illustrate a modified form 90 of operating mechanism, which comprises a housing 30 provided with a bracket 31 for embracing the sash rail 12. A helical spring 32 has its inner end held adjustably 95 in position in said housing by means of a shaft 33 to which it is fastened and which is held against rotation in said housing by a ratchet 34 and a pawl 35. The shaft 33 and its attached ratchet 34 may be rotated by means of a crank, as shown in dotted 100 outline, or by means of a suitable wrench, in order to adjust the spring 32 to the proper tension whenever it becomes slack. A guide flange or means 36 is also provided at the front of the housing to aid in retaining the 105 cleaning means against the window. The free end of the spring is attached to the diverging arms 16 of the cleaning means 15 as described in the preferred form.

In Fig. 5, a further modified form 110 of operating means is shown, which comprises a leaf spring 40 fastened with one

end to a bracket 41 which clasps the sash rail 12 of the window 13. The other end of said spring slides through a guide bracket 42 which also clasps said sash rail 12, like 5 the bracket 41, and carries a front guide bar 43 to aid in retaining the cleaning device in contact with the window. The free end of said spring is fastened to the diverging arms 16 of the cleaning means 15, as 10 previously described.

The manner of mounting and operating each of the modified forms is substantially the same as described in regard to the preferred form.

15 While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come 20 within the scope of the appended claims.

25 Having described our invention, what we claim as new and desire to secure by Letters Patent is:

1. A window cleaning device provided with a housing having means thereon for 30 detachably clasping a window sash rail, reversible cleaning means including bristles on one side and a rubber strip on the opposite side for washing and drying the window, means in said housing connected with 35 said cleaning means for moving said cleaning means along the window in one direction, and flexible means for operating the device manually from the inside of the window in the opposite direction.

40 2. A window cleaning device provided with a housing having its lower wall extended in the form of a channel-shaped clip for detachably mounting said device on the sash rail of a window, reversible cleaning 45 means for washing and for drying either side of the window, a spring on said housing and connecting said cleaning means with said supporting means for automatically moving said cleaning means to the upper 50 part of the window, and flexible means

operable from the inside of said window for drawing said cleaning means downward on said window.

3. A window cleaning device provided with a housing and means for mounting it 55 on a window sash, means for cleaning the window, a spring fastened with one end in said housing and the free end extending from said housing and fastened to said cleaning means, means connected with the 60 inner end of said spring for readily regulating the tension of said spring, and means for manually actuating said cleaning means against the tension of said spring.

4. A window cleaning device provided 65 with a housing and means on said housing for detachably clasping the sash rail of a window, means for cleaning the window, a helical spring in said housing and having 70 its inner end fastened to said housing and its outer end extending through said housing and fastened to said cleaning means, pawl and ratchet means for adjusting the tension of said spring, and a cable for actuating said device against the action of said springs. 75

5. A window cleaning device provided 80 with a housing and a channel member integral with a wall of said housing for detachably mounting said housing on the sash rail of a window, cleaning means including 85 bristles on one side and a rubber strip on the opposite side for washing and drying the window, a helical spring in said housing and having its inner end fastened in said housing and its outer end extending through 90 said housing and fastened to said cleaning means, means for taking up the inner part of said spring to adjust it for tension, and a cable releasably attached to said cleaning means for actuating said device against the tension of said spring.

In testimony whereof we have signed our names to this specification in the presence of two subscribing witnesses.
